OF CLEVELAND, OHIO, A CORPORATION OF OHIO.

SAND-SUPPORTING DEVICE FOR MOLDING-FLASKS.

1,159,114.

Specification of Letters Patent.

Patented Nov. 2, 1915.

Application filed April 11, 1914. Serial No. 831,306.

To all whom it may concern:

Be it known that I, HARRY J. SMITH, a citizen of the United States, residing at Lakewood, in the county of Cuyahoga and 5 State of Ohio, have invented new and useful Improvements in Sand-Supporting Devices for Molding-Flasks, of which the following is a specification.

This invention relates to a sand supporting device for molding flasks in which sand molds are produced and more particularly to a flask of this character provided with means which are mounted on the walls of the mold and support the sand between 10 these walls so as to prevent breakage of the sand mold during the operation of the mold and pattern.

It is the object of this invention to produce a sand supporting device of this character which is comparatively simple and inexpensive in construction, which can be readily adjusted to suit different forms of patterns, which has a comparatively large holding surface, and which is less exposed 20 to the destructive action of the gases generated during the casting operation than the devices of this character heretofore in use.

In the accompanying drawings: Figure 1 is a vertical longitudinal section of a molding flask equipped with my improved sand supporting device. Fig. 2 is a fragmentary top plan view thereof. Fig. 3 is a vertical transverse section thereof taken in line 3—3, Fig. 1 but showing the pattern on the mold 30 board omitted.

Similar characters of reference indicate corresponding parts throughout the several views.

My improved sand supporting device is 40 applicable to various kinds and forms of molding flasks, that shown in the drawings, for example, being of rectangular shape and comprising transverse walls 1 and longitudinal walls 2 connecting opposite ends of 45 the transverse walls. This flask is adapted to rest upon the usual mold board 3 which is provided on its upper side within the flask with one or more patterns 4 so that upon filling the space within the flask and above the 50 pattern board with sand and then separating the flask from the board an impression of the pattern will be left on the underside of the sand, in the usual and well known manner.

55 In order to hold the sand reliably in place

and prevent the same from breaking or dropping out of the flask when separating the flask and pattern board an intermediate sand supporting device is provided which embodies my invention and is constructed as 60 follows: 5 represents one or more supporting bars extending across the space within the flask above the pattern and secured at its opposite ends to the inner side of two opposing walls of the flask by means of flanges or 65 lips 6 arranged at opposite ends of each supporting bar and secured to these walls by means of nails 7, as shown in Figs. 2 and 3, or by any other suitable means.

At different points throughout the length 70 of each supporting bar the same may be provided with laterally projecting loops or sockets 8 which open vertically and each of which is adapted to receive a nail 9, as shown in Figs. 1 and 3, or the like, which 75 nails are preferably inserted vertically or substantially so in these loops with their heads at the lower ends thereof so that they form a plurality of anchors which are embedded in the sand as the same is filled into 80 the flask and operate to support this sand and prevent breakage of the mold when the flask and pattern board are separated.

The supporting bar is preferably constructed of sheet steel or similar metal and 85 the loops are preferably formed by displacing a portion of the metal stock of this bar laterally at intervals out of the same to such an extent as will form the loops and leave vertical openings or sockets into each of 90 which an anchoring nail is adapted to be inserted or driven and held frictionally therein by the resilience of the loop, bar and the nail. Owing to this resilience each of the nails may be adjusted vertically in its particular loop to suit the position of that part 95 of the sand mold which it is intended to support and the same may also be tipped in a direction lengthwise of the bar and held frictionally in this position to suit any 100 peculiarities of the pattern from which a sand mold is being made. The nail supporting loops are preferably constructed in the form of two longitudinal rows on opposite sides of the supporting bar and the loops 105 on one side of the bar alternate with the loops on the other side so that the several loops form a staggered arrangement of the same as a whole. By this means the supporting effect of the two rows of nails which 110

are mounted on each bar is spread over a greater area than would be the case if the nails were all arranged on the same line, thereby increasing the efficiency of this sand supporting device without increasing its cost.

Inasmuch as the lower edge of the supporting bar is continuous from one end of the same to the other the sand of the mold fits closely against this part of the bar and reduces to a minimum the possibility of any of the gases generated during the casting operation from passing upwardly along the supporting bar and reaching the supporting loops which carry the nails, thereby reducing the tendency of these gases to destroy these nail supporting loops and prolonging the life of the sand support accordingly.

My improved sand supporting device for molding flasks is exceedingly simple in construction, the same is very efficient in operation and can be readily adjusted to various kinds of patterns and it can be produced at comparatively low cost.

I claim as my invention:

1. A sand supporting device for molding flasks comprising a single bar having nail loops projecting laterally from the side thereof at a distance from the upper and lower edges of the bar.

2. A sand supporting device for molding flasks comprising a single bar having nail loops projecting laterally from the side thereof at a distance from the upper and

lower edges of the bar and the inner sides 35 of said loops being arranged at a distance from the adjacent side of the bar.

3. A sand supporting device for molding flasks comprising a single bar having nail loops projecting laterally from the side 40 thereof at a distance from the upper and lower edges of the bar, the lower edge of said bar being continuous or unbroken, and the inner sides of said loops being arranged at a distance from the adjacent side of the 45 bar.

4. A sand supporting device for molding flasks comprising a bar provided on its opposite sides with rows of laterally projecting loops which are bent out of the stock of 50 the bar and each of which is adapted to receive an upright nail.

5. A sand supporting device for molding flasks comprising a bar provided on its opposite sides with rows of laterally projecting 55 loops which are bent out of the stock of the bar and each of which is adapted to receive an upright nail, the loops on one side of the bar being arranged to alternate with those on the other side of the same for producing a staggered arrangement of these loops.

Witness my hand this 9th day of April, 1914.

HARRY J. SMITH.
